UNITED STATES PATENT OFFICE

JOHANNES MARUHN, OF BERLIN-FRIEDENAU, AND LUDWIG TÜBBEN, OF BERLIN-NICOLASSEE, GERMANY

METHOD OF PRODUCING HYDROCARBONS

Application filed May 23, 1931, Serial No. 539,548, and in Germany December 16, 1925.

This application forms a continuation in part of Serial No. 434,695 which has matured into Patent No. 1,807,122 on May 26, 1931, the only added matter beyond the description in the parent application being found in the last half of the next to the last paragraph of the specification immediately preceding the claims.

It is known to initiate the chemical reaction between coal, solid and liquid hydrocarbonaceous substances and hydrogen, without the co-action of suitable catalysts, under a high pressure and at a suitably high temperature by employing a plurality of apparatus, such as pumps, compressors, heating tubes, autoclaves, and the like, connected with one another in series, and to carry out the process within a shorter or longer period for the purpose of obtaining hydrogenation products, oils, and gases.

It is also known to obtain water-gas from liquid hydrocarbons, earth-oil, brown-coal tars and pit-coal tars, as well as the products of distillation thereof, by carrying out the gasification in the interior of internal combustion engines, the requisite splitting process taking place during the expansion stroke, and the liquid material being introduced in the form of hydrocarbons in a manner resembling that used with Diesel motors.

Now, the present invention consists in the use of a suitably designed compression space of a hydraulic compression device, for instance such as shown and described in the German patent-specification 350,619, in order to convert in that compression space, and in one, continuous procedure carbonaceous substances, for instance fine-coal, brown-coal, pit-coal and coke, preliminarily dried and pulverized in known manner, or heavy oils, directly into distillable oils by introducing the starting substance into said compression space, and adding hydrogen under high pressure and at a corresponding temperature, without the co-action of a substance adapted to act as a catalyst.

A hydraulic press having a suitably designed compression space is particularly useful for carrying out our improved method, that is to say, for employing solid hy-

drocarbons or heavy oils as starting materials and effecting the known hydrogenating and splitting reactions in a direct way without the insertion of special high-pressure apparatus or autoclaves into the path of the respective material.

As regards the hydrogenation of coal, this process is carried out in the manner described hereinafter; which description is true also as regards heavy oils.

Using the compression space of a hydraulic press renders possible without any difficulty the working of finely pulverized coal without any addition of oil, or turning the coal into a coal-oil-paste. There is attained in that space a direct and intimate mixture of the substances concerned and a reaction with hydrogen which can be carried out under a high pressure that may be regulated as desired, and at a temperature of any height; catalysts are not used and the pressure used during that period in which the reaction takes place may be uniform or variable as desired or preferred.

The difficulty often experienced with the known hydrogenating processes of introducing the coal in unmixed state and in solid form into the high-pressure apparatus is done away with, as the hydraulic compression device permits the introduction of the pulverized coal into the pressing space at a pressure of 1500 atm. and even higher, as is done with brown-coal briquetting machines. Besides said advantage, another advantage resides therein that, in contradistinction to all known apparatus for the hydrogenation of coal, the employment of the hydraulic press entails a considerable simplification of the process, and renders it cheaper. It must be borne in mind that the hydraulic press presents, for initiating and carrying out the process, and above the known special high-pressure compression plants, as used heretofore, the important technical, chemical, and economical advantages that the press we make use of is very compact, requires, therefore, only little space, and that the requisite devices and instruments for measuring the pressure and the temperature, for admitting the substances concerned, and for regulating

the supply thereof can be easily watched, are easily accessible, and can likewise easily be exchanged, if necessary. These features are the more important, as there may be sulphur in the coal in spite of the conversion of the sulphur into sulphate of iron by an addition of iron oxide. Also the reduction of the volume or bulk of the material by means of the high pressure is very important for 5 the apparatus, and the expenses caused by working under pressure are reduced.

The results attained when operating according to our invention depend, of course, as regards the quality of the product, upon 15 the quality of the starting materials or substances, also upon the kind of the reduction agent used, but, on the other hand, they are independent of the process per se by reason of the new and particular employment of a 20 technical apparatus which can be used in connection with all reaction agents, reaction pressures, and reaction temperatures that have become known and have been used up to now. The object of the process per se is 25 to obtain in a simple manner distillable oils from solid hydrocarbons in the form of sufficiently, preliminarily dried and finely pulverized brown-coal or pit coal, as well as fine coal, and from heavy oils.

30 In experimental trials in which brown-coal semi-coke was used as starting material there has been obtained, for instance, an amount of distillable oil equal to from 40 to 60% in weight of that starting material, from 35 63 to 65% of that oil boiling at 280° C., 20% at a higher temperature, and the residue amounting to 17% having a softening point of 87° C. That a part of the oxygen contained in the coal is converted into water, 40 another part is reduced to the hydroxyl group, that is to say, to phenols, a part of the often present sulphur is converted into ammonia, and finally, another part is converted into gasiform hydrocarbons, all of 45 which are known and comprehensible phenomena which do not impair the success of the direct production of distillable oils.

The hydraulic press for carrying out our improved process is illustrated diagrammatically and by way of example on the accompanying drawings in which Figure 1 is 50 an axial section through the press, Figure 2 is a front view of the same, and Figure 3 is a detail, all as fully described hereinafter.

55 On the drawings, *a* is a cast-iron body and *b* a steel cylinder into which is inserted a working cylinder *c*. The two cylinders can easily be removed from the body in order to 60 be repaired etc., if necessary. Into the cylinder *b* is cast a coil *d* through which hot oil is to be conducted in order to heat the reaction mass contained in the cylinders. The plunger *e* which fits into the cylinder *c* has 65 at its inner end or face a steel cup *r* which

serves as a packing and tightening member for the plunger in the cylinder *c*.

This cylinder *c* is designed as a sleeve in the cylinder *b*, and this latter cylinder *b* is designed as a truncated cone at its closed 70 end and is there provided with a passage *l*, as well as with a transversely located slot into which two iron ledges *f* (Figs. 2 and 3) can be shoved; the sectional area of the passage *l* can be varied by said ledges which 75 can be shoved towards, and away from one another and can form between them a gap of larger or smaller size, but the passage mentioned can also be completely closed by said ledges, as will be obvious in view of 80 the particular shape of the ledges, as shown in Fig. 3. When that opening is closed, the reaction mass can be subjected to the requisite pressure which may amount to 1000 atm. and even more, and can be attained without 85 particular pains and without any danger for the apparatus.

In the cylinder *b* is passage *m* and in the body *a* is a passage *n*, and a piece of tube *o* connects the two passages with a supply hopper *p*. The tube *o* is traversed by two slides *h* and *i* so that the material to be fed into the cylinders *b* and *c* can be introduced in certain individual amounts corresponding to the space between said two slides, and without 95 bringing the interior of the cylinders in communication with the atmosphere.

The hydrogenating gas is supplied through the pipe *k* which terminates in the passage *n*.

If pulverulent coal is used, the operation 100 proceeds in this way that the hydrogenated mass is compressed by the plunger *e* so much that space for the reception of another amount of the material and of the requisite amount of gas is provided, and the stroke of the plunger is so determined that the new or fresh amount is compressed only after the plunger has covered and closed the orifice of the passage *m* so that the hydrogen is prevented from escaping through that passage. 105 According to the present application, the reaction takes place gradually after the press plunger has reached its left end position (several minutes according to pressure, temperature, etc.). When the press plunger is stationary, the full pressure must be exerted during the said period on the material to be treated. It is obvious that a crank press is 110 by no means suitable for that purpose.

As regards the actuation of the press, we 115 refer to the above-mentioned German patent-specification 350,619 in which matters are fully shown and described.

We claim:

A method of producing liquid hydrocarbons of low boiling point by hydrogenating and converting carbonaceous substances selected from a group comprising finely pulverized coal, heavy oils and mixtures of pulverized coal and oil at an increased temper- 120 125 130

ature and under high pressure of free hydrogen-containing gas; said method consisting in feeding to a reaction zone a mixture of hydrogen-containing gas and said carbonaceous substances without a catalyst, heating and gradually compressing the mixture into a smaller volume in a part of said zone until the maximum reaction pressure of at least 1000 atmospheres is reached, maintaining said maximum pressure several minutes and finally removing the product from said reaction zone.

In testimony whereof we affix our signatures.

15   JOHANNES MARUHN.
              PROF. DR. LUDWIG TÜBBEN.
